ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

SLEEVE VALVE ENGINE CYLINDER HEAD

Application filed November 16, 1927. Serial No. 233,550.

This invention relates to internal combustion engines and refers more particularly to the sleeve valve type of engine. In this type of engine the upper extremity of the sleeve ordinarily works in a pocket formed between the cylinder head and cylinder. While the cylinder head is ordinarily jacketed for cooling water, the amount of available jacketing is limited due to spark plug location and general arrangement of parts. As a result the sleeve jacket tends to become overheated resulting in formation of steam pockets, carbon accumulation and general inefficient operation of the engine.

One of the objects of my invention resides in providing means for overcoming the above objectionable characteristics. To this end I have provided improved means associated with the cylinder head for causing a positive circulation of cooling water for cooling the cylinder head, sleeve pocket, and spark plug.

I have provided a member preferably in the nature of a simple sheet metal stamping associated with the cylinder head for guiding the water in the desired circulating path. One feature of my invention resides in a construction whereby the sheet metal member referred to may be readily removed without disturbing the sealing gasket or other sealing means ordinarily provided for the cylinder head and cover.

Further features and advantages of my invention reside in the simplicity of the parts, lightness of weight, and ability to be manufactured at low cost.

Further features of my invention reside in the novel combination and arrangement of parts more particularly hereinafter described and claimed.

Referring to the accompanying drawings in which like reference characters represent corresponding parts,

Fig. 1 is a sectional elevation view through

a typical engine cylinder showing my invention,

Fig. 2 is a sectional view at right angles to Fig. 1 through the line 2-2 of Fig. 1, and

Fig. 3 is a perspective view of the water deflecting member.

In the drawings reference character 10 represents one or more engine cylinders with associated piston 11 and sleeve valve 12, the latter for illustration being shown as the "Burt-McCollum" single sleeve valve type in which the sleeve is moved in a combined reciprocating and oscillating path with respect to the sleeve axis in moving the sleeve ports 13 to function with the cylinder ports 14.

The cylinder is closed at the top by a cylinder head 15 which may be formed with walls 16 and 17. The wall 16 together with the associated cylinder forms a valve pocket 17^a accommodating the movement of the upper portion of the sleeve valve 12. The wall 17 is spaced from the wall 16 to form the cylinder head cooling water jacket 18 and also defines the combustion chamber 19. The wall 17 may be extended to provide a barrel 20 with the spark plug opening 21. The cylinder head 15 may be secured to the cylinder by studs 22 at the corners of the cylinder head flange 23.

The cooling water from jacket 24 is open for communication with the cylinder head jacket 18 through opening 25 preferably mainly along one side only of the cylinder head. For guiding the water from opening 25 I have provided a member 26 preferably formed of a sheet metal stamping. The member 26 may be formed with wall 27 spaced from the side of the cylinder head adjacent the opening 25, side walls 28, and top wall 29. The water in moving across the cylinder head is caused to circulate downwardly into the jacket 18 by reason of the cylinder head baffles 30 which may be cast

80
85
90

with the cylinder head and which divide the jacket 18 longitudinally. Cooperating with baffles 30 are baffles 31 preferably formed integrally with the main body of the member 26. The top wall 29 is formed with a semi-circular or recessed portion 32 preferably open at an edge of said member and engageable with the barrel 20 preferably below the sealing structure or ring 33. A nut 34 threadedly engages barrel 20 for clamping the cylinder head cover 35 and sealing ring 33 in position as shown in the drawings. One feature of my invention resides in the manner in which the barrel conveniently locates the member 26 in its proper position, at the same time permitting removal of this member (after removing nut 34 and cover 35) independently of the sealing ring 33. This is quite important since the sealing ring 33 after use becomes "worn in" affording a tight sealing joint, it being desirable not to disturb this joint in removing the cylinder head. In order to further prevent displacement of the member 26 as might occur from the water flow, I may provide a lug 36 projecting inwardly from cover 35 and either engaging the member 26 or in proximity thereto. If desired the projection or lug might be formed with the member 26 and engageable with the cover 35 as will be readily understood.

The cooling water may be circulated throughout the entire system by the usual water pump (not shown), the water being returned to the usual radiator by a header 37 on the outlet side of baffles 30, 31.

My invention is equally well adapted for use with various types of sleeve valve engines such as multiple or single sleeves having various movements.

What I claim as my invention is:

1. An internal combustion engine of the sleeve valve type comprising in combination, a water jacketed cylinder, a piston operable therein, a water jacketed cylinder head forming a sleeve pocket with the cylinder and provided with a barrel portion, a cylinder head cover through which said barrel extends, a sealing ring between the barrel and cylinder head cover, and a member intermediate the cylinder head cover and cylinder head having a recessed portion embracing the barrel for locating the member in position, said recess being open at an edge of the said member, said member having a depending web constructed to form a water deflecting means cooperating with the cylinder head jacket for directing water from the cylinder jacket to flow generally downwardly into and across the cylinder head.

2. An internal combustion engine of the sleeve valve type comprising in combination, a water jacketed cylinder, a piston operable therein, a water jacketed cylinder head forming a sleeve pocket with the cylinder and

provided with a barrel portion, a cylinder head cover through which said barrel extends, a sealing ring between the barrel and cylinder head cover, and a member intermediate the cylinder head cover and cylinder head having a recessed portion embracing the barrel for locating the member in position, said member having a depending web extending substantially perpendicular to the top wall of the member and constructed to form a water deflecting means cooperating with the cylinder head jacket for directing water from the cylinder jacket to flow generally downwardly into and across the cylinder head, said member being removable independently of the sealing ring.

3. An internal combustion engine of the sleeve valve type comprising a cylinder, a cylinder head having a water jacket portion depending into said cylinder and an upstanding barrel portion, a cylinder head cover, a member within the cover cooperating with the cylinder head to direct cooling water into the cylinder head jacket, sealing means between the barrel and cylinder head cover, said member having a portion engageable with the barrel, said member being removable with respect to the cylinder head and cylinder independently of the sealing ring.

4. An internal combustion engine of the sleeve valve type comprising in combination, a water jacketed cylinder, a piston operable therein, a water jacketed cylinder head forming a sleeve pocket with the cylinder and provided with a barrel portion, a cylinder head cover through which said barrel extends, a sealing ring between the barrel and cylinder head cover, and a sheet metal member intermediate the cylinder head cover and cylinder head having a recessed portion opening at an edge of the member and embracing the barrel for locating the member in position, said member provided with a depending web extending to right angles to the plane of the top wall of said member and constructed to form a water deflecting means cooperating with the cylinder head jacket for directing water from the cylinder jacket to flow generally downwardly into and across the cylinder head.

5. An internal combustion engine of the sleeve valve type comprising a cylinder, a cylinder head having a water jacket portion depending into said cylinder and an upstanding barrel portion, a cylinder head cover, a member within the cover cooperating with the cylinder head to direct cooling water into the cylinder head jacket, sealing means between the barrel and cylinder head cover, said member having a portion engageable with the barrel, said member being in the nature of a sheet metal stamping and being removable with respect to the cylinder

head and cylinder independently of the sealing ring.

6. A sleeve valve engine comprising a cylinder, a cylinder head, a cover member, a member within the cover for guiding cooling water into the cylinder head, said second member having a recessed portion engaging the cylinder head for locating the second member in position, and means on one of said members and engageable with the other preventing displacement of the second member from the water flow.

7. A sleeve valve engine comprising a cylinder, a cylinder head, a cover member, a member within the cover for guiding cooling water into the cylinder head, said second member having a recessed portion engaging the cylinder head, and a lug projecting inwardly of the cover member engageable with the second member for preventing displacement thereof from the water flow.

8. A sleeve valve engine comprising a cylinder, a cylinder head, a cover member, a member within the cover for guiding cooling water into the cylinder head, a sealing joint between the cylinder head and cover member, said second member having a cylinder head engaging portion independent of the sealing joint.

30 9. A sleeve valve engine comprising a cylinder, a cylinder head member, a cover member, an element within the cover member for guiding cooling water into the cylinder head, said element having a portion co-operating with the cylinder head member for locating said element in position, and means on one of said members and engageable with said element preventing displacement of the element from the water flow.

40 10. A sleeve valve engine comprising a water jacketed cylinder, a water jacketed cylinder head provided with a barrel portion, a cylinder head cover through which the barrel extends, a sealing ring between the barrel and cylinder head cover, and a member intermediate the cylinder head cover and cylinder head having a recessed portion opening at an edge of the member and partially surrounding the barrel, said recessed portion of the member engaging the barrel adjacent the sealing ring, said member being removable with respect to the cylinder head and cylinder independently of the sealing ring.

55 11. A sleeve valve engine comprising a water jacketed cylinder, a water jacketed cylinder head provided with a barrel portion, a cylinder head cover through which the barrel extends, a sealing ring between the barrel and cylinder head cover, and a member intermediate the cylinder head cover and cylinder head having a recessed portion opening at an edge of the member and partially surrounding the barrel, said recessed portion of the member engaging the barrel adjacent the sealing ring, the mem-

ber provided with a depending web extending in a plane parallel to the axis of the barrel, the inner edge of said web engaging the side of the barrel, said web providing a water deflecting means cooperating with the cylinder head jacket for directing water from the cylinder jacket to flow generally downwardly into and across the cylinder head.

In witness whereof, I hereunto subscribe my name this 14th day of November, A. D. 1927.
